UNITED STATES PATENT OFFICE

DAVID E. DAY, OF LOS ANGELES, CALIFORNIA

PROCESS OF AND APPARATUS FOR DISTILLING AND CRACKING HYDROCARBON OILS

Application filed August 21, 1922, Serial No. 583,170. Renewed December 12, 1927.

This invention relates to a process and apparatus for heat treating hydrocarbon oils and pertains particularly to the distillation and cracking of heavy petroleum oils in such a way that carbon incrustations within the apparatus may be avoided.

The invention is conducted in apparatus in which a plurality of parallel arranged pipes are so connected to each other and to a central hollow shaft about which they are grouped and with which they rotate, that oil may be introduced through the shaft and passed progressively through each of the pipes and finally discharged from an axially located discharge connection. During this operation heat is applied to the pipe arrangement in such a way that the pipes farthest from the center are subjected to the highest degree of heat, the temperature of which is sufficient to effect cracking of the oil in the pipes.

One of the particular features of the present invention relates to the process and apparatus by which liquid oil is treated in a relatively thin stream and at a very high speed by being passed through an exteriorly heated pipe which contains a spacing bar member extending lengthwise therethrough, thus increasing the speed of a given cross section of oil as compared to a cross section of oil in a part of the tube in which the rod does not extend.

One outstanding feature of the process and apparatus of this invention includes the high speed treatment of oil combined with the results produced by having a freely movable abrading rod positioned within each of the pipes which rotate with the center shaft and revolve about it.

Another particular feature of the present invention is directed to the particular treatment of the oil and the sequence in which it is passed through the apparatus. This sequence includes the introduction of the fresh or cold oil to a center axial pipe, the passage of the cold oil from the central pipe to the outer pipes of a revoluble series of pipes, the flowing of the oil from the outer pipes to and through the more centrally located pipes, and finally, the withdrawal of the oil from the more centrally located pipes. In this cycle

of treatment, because in the revolution of the pipe assembly the outer pipes are nearer the source of heat, the cold oil is thus subjected to a higher degree of heat than the oil in the inner or more central pipes. In handling certain types of oil, particularly gas oils under pressure, and in using the retort as a topping still, it is desirable to use this sequence of treatment just described. This is particularly desirable where a uniform treatment is needed because the oil instead of being heated progressively to a constantly higher temperature is carried through the hottest tube first and then through the relatively cooler tubes, the tendency being to keep the oil in a constant temperature.

Other features and advantages are described and claimed in the following specification and claims, and illustrated in the accompanying drawings, in which:

Figure 1 represents a side elevation of a partial section taken substantially centrally and on the line 1-1 of Figure 2 through the length of the apparatus, illustrating the furnace and central pipe in section;

Figure 2 is an end view of the structure shown in Figure 1 taken on the line 2-2 of Figure 1, looking in the direction of the arrow;

Figure 3 is a sectional view taken on the line 3-3 of Figure 1, looking in the direction of the arrow;

Figure 4 represents a sectional view, partly broken away, showing the position of a hollow rod within one of the pipes;

Figure 5 represents a cross sectional view taken on the line 5-5 of Figure 4;

Figure 6 shows a modified arrangement in which a plurality of round, solid rods are used;

Figure 7 represents a cross sectional view showing how a square rod may be used;

Figure 8 represents a portion of a twisted solid rod used within the treatment pipes;

Figure 9 represents a view similar to that of Figure 4 except that the rod within the tube is spaced centrally from the tube walls;

Figure 10 is a cross sectional view taken on the line 10-10 of Figure 9;

Figure 11 represents diagrammatically a

pipe arrangement in which the diameter of the pipes is progressively reduced from the inlet to the outlet for progressively increasing the speed of travel of the oil, the oil being led first through the inner pipes;

5 Figure 12 is a diagrammatic view in which pipes of the same size are used and rods are positioned only in the tubes near the outlet;

Figure 13 is a view similar to that of Figure 12, illustrating pipes of uniform size and progressively larger rods within the pipes from the inlet to the outlet; and

10 Figure 14 is a view similar to that of Figures 12 and 13 illustrating uniform sized pipes and a progressive increase in the number of rods from the inlet to the outlet end.

15 Referring in detail to the figures of the drawings, like numerals refer to like parts in the different figures. The furnace structure of suitable concrete, brick, or other building material is indicated at 1. A fire box 2 having an opening 3 is shown in the lower part of the furnace 1, and a stack, not shown, may lead from the upper portion of the furnace at one end thereof.

20 Extending lengthwise through the furnace are a plurality of pipes connected together to form a rotatable pipe still, the details of which will now be described. A centrally located horizontal pipe or tube 4 is journaled at opposite ends of the furnace in the supporting bearings 5 which are cooled or lubricated by cooling liquid or oil in a channel 5^a formed in the upper portion of the bearing 5.

25 The bearing is mounted at the upper end of supporting legs or braces 6, which in turn have a base portion 7 mounted at one end on a masonry support 8 and secured thereby by fastening screws or bolts 9, and at the opposite end adjacent the furnace door opening the bearing 5 is supported on girders 10 which bridge the space opposite the furnace opening 3. The bearing is provided with a suitable bushing of cast iron encircling the pipe 4 as indicated at 11, and the bushing is

30 preferably keyed to the pipe 4.

In the particular arrangement of still illustrated, twenty-nine pipes are grouped about the central pipe 4. These pipes are numbered 35 consecutively from 12 to 40, and the particular sequence of their connection may be understood from an inspection of Figures 2 and 3 which show one arrangement of inlet and outlet connection in which the oil is first led to the outer pipes and then taken off from the inner ones. In Figures 11-14, inclusive, a different arrangement of connection is provided by which oil is led first to the inner pipes and then taken off from the outer pipe.

40 These pipes 12-40, inclusive, are positioned and fixed in parallel relation and are grouped around the central pipe 4 and have their ends connected by return bend portions 41 in such a manner that the pipes are connected in series, the hollow central pipe 4 being in ported

communication with one of the pipes located farthest from the center according to Figures 2 and 3, and the other pipes being progressively connected to those located toward the center of the group, from which latter a return connection is made to the hollow pipe member 4, as will be explained. At the opposite ends of the furnace, and near the ends of the pipes, are spacing plates 42 which have a

70 circular periphery and through which the individual pipes project and have a relatively tight connection. The purpose of these spacing plates 42 is also to prevent the escape of heat and heating gases from the furnace and to confine the heat and the heating gases to the

75 space immediately about the group of pipes 12-40. To further provide for a tight fit at the periphery of the plates 42 a complementary stationary annular plate 43 is mounted at each end of the furnace and in close, but

80 spaced relation to the plates 42. The plates 42 have an intimately projecting flange 42^a which is adapted to move in a channel shaped extension 43^a continued from the plate 43. Thus in the rotary movement of the group of

85 pipes and the plates 42, the tortuous passage provided between the parts 42^a and 43^a limits the escape of the heating gases from the furnace. The plates 42 are preferably welded to the exterior of the pipe 4 or otherwise 90 braced so as to move with the pipe 4 during the rotation of the pipes with and about the pipe 4 as an axis. The pipes 12-40, inclusive, are illustrated as having flanges 44 at their

95 ends to which may be secured by bolts, not illustrated, the corresponding flanges of the end bend portions 41. In order to make possible a compact assembly, and also provide space for the flanges 44, the pipes 12-40 are 100 positioned in staggered endwise relation so that next adjacent pipes project alternately further from the plates 42 on the opposite ends of the rotatable assembly.

105 The particular apparatus and the manner of introducing and leading off the oil treated will now be described. An intake pipe for fresh oil is indicated at 45, and it will be noted that this pipe is slightly off center with respect to the center of the pipe 4. An outlet pipe for oil which has been treated is indicated at 46, and this pipe is illustrated as

110 in alignment with the center of the pipe 4. Both of these pipes 45 and 46 are illustrated as screw threaded in a stuffing box structure having a stationary block member 47, which 115 in turn has cylindrical sleeves 47^a and 47^b providing an annular space therebetween. The purpose of this arrangement is to provide an oil tight fit against the movable portion of the still, as will be shown. The pipe

120 4, at one side of the bearing 5, has a plate 48, having a cylindrical flange 48^a projecting therefrom which is adapted to fit in the space between the sleeves 47^a and 47^b. A spring-held annular clamping flange 49 fits over the

outer end edge portion of the plate 48 and has a central opening 49^a through which a central extension 48^b projects from the plate 48 and is coupled onto the central pipe 4 at 48^c. The flange 49 is secured to the plate 47 by bolts 50 which have heads 51, nuts 51^a, and springs 52, which latter are held and moved in openings 53 formed in the rear of the flange 49. In practice a series of the spring held bolts 50 are positioned around the margin of the plate 48 and the flange 49 to yieldably hold the plate 48 and the block member 47 in engagement. The position of the flange 48^a between the sleeves 47^a and 47^b serves to assist in centering the parts and to provide an oil tight seal. Packing material 54 is provided between 47^a and 47^b at the inner end of the space to assist in preventing the leakage of oil, and oil vents are indicated at 54^a through the block 47. A similar arrangement of concentric flanges is provided to maintain an oil tight but rotatable connection between the oil inlet passage and the oil outlet passage as will now be described. The oil outlet pipe 46 terminates at the center of the block 47. An inner oil outlet pipe 55 is positioned centrally within and spaced from the pipe 4, and extends therethrough from a point on the still side of one bearing and terminates near the inner end of the pipe 46 and in alignment therewith. The opposite and still end of the pipe 55 is connected to the pipes of the still, as will be described hereinafter. The block 47 has a second set of concentric flanges corresponding to the flanges 47^a and 47^b, and indicated at 47^c for the inner flange, and 47^d for the outer flange, and both of them serving to provide an annular space therebetween. Fitted into this space is a cylindrical flange 56 which closely encircles the pipe 55 and is fixed to it by clamping screws 57. The extreme outer end of the pipe 55 is closely rotatably fitted into the central opening within the flange 47^c. The inner end of the part 56 has a plurality of spaced fingers 58 projecting along the pipe 55 and serving to space the inner end of the flange 56 from the next adjacent face of the part 48 so that fresh oil may pass between the fingers 58 from the pipe 45 inwardly and along the exterior of the outlet pipe 55. The space between the flanges 47^c and 47^d is also provided with packing material 54 and similar openings leading thereto through the block 47 are indicated at 54^a. This description applies to the stuffing box end of the apparatus.

The end of the apparatus opposite to the stuffing box is used for access to the fire box 60 through the doorway 3. The end of the central pipe 4, farthest removed from the stuffing box, is provided with a cover plate or cap 4^a, to tightly close that end of the pipe and prevent oil from leaking. The cap 4^a serves also for inspection and cleaning of the

interior of the pipe 4. Between the plate 42 and the end bearing near the cap 4^a is a lead off pipe 4^b extending from the central pipe 4 to the pipe 12, the first of the series of the pipes 12-40, inclusive, located in the outer group of pipes. The last pipe of this series, 40, is illustrated as one of the inner group of pipes and is positioned between the center and the pipe 12. The end of the pipe 40 next adjacent the stuffing box is connected to the outlet pipe 55 by a pipe 55^a which extends centrally toward the central pipe 4 between the plate 42 and the bearing, projects through the pipe 4, and is continued within the pipe 4 as the pipe 55.

A sprocket wheel for applying power to revolve the still is indicated at 59 on the central pipe 4 and is located between the stuffing box and the adjacent bearing.

Scraping means or scouring means is provided for the interior of each of the pipes 12-40, inclusive, and also, if desirable, for the interior of the central pipe 4, by rods 60 which extend lengthwise of the pipes and which are inserted from the ends of the pipes when the bends 41 are removed. These rods 60 have preferably a cross sectional area at least as great as half the cross sectional area of the bore of the pipes. The rods normally rest on the inner lower surface of the pipes 90 and are adapted to slide and roll around the inner surface of the pipes as the latter are revolved about the pipe 4 as an axis. In this movement the rods serve as abrading elements and grind away any carbon which may be deposited on the inner surfaces of the pipes. The rods serve also to increase the speed of the oil as it flows through the pipes, this invention having shown that a given cross section of oil flows much more swiftly 100 through the portion of the pipe containing the rod than through a portion of the pipe, such as the end portions or a similar section without a rod, in which no spacing member is positioned. The rod, in addition to increasing the speed of the oil, serves to reduce the thickness of the body of oil to be heated in any given cross section of oil in the part of the pipe not containing the rod. This relatively thin body of oil is accordingly 110 much more readily and quickly heated, and because of its increased speed, reduces to a minimum the formation of carbon on the inner surface of the pipes, the speed serving to wash away carbon before it has opportunity to become deposited. In Figure 4 a typical pipe is shown in section illustrating also in section a hollow rod 60 having the ends thereof plugged at 61, and having an opening 62 through the wall of the hollow rod for the equalization of pressure. This form of rod provides a light structure which serves efficiently for the removal of carbon and provides sufficient cross sectional area to reduce the volume of oil within the large pipe with- 120

out adding the undesirable weight which would be provided by a solid metal rod. The structure of Figure 4 is shown in cross section in Figure 5. Figure 6 shows a modified arrangement in which a plurality of rods, three in this view, are used. A plurality of rods may serve particularly efficiently in certain instances because the tumbling action of the rods is multiplied and the removal of carbon is thus made more positive. Figure 7 shows a form of square rod, and Figure 8 shows a fragmentary view of a twisted arrangement of solid rod, which, because of its cutting edges, has been found particularly efficient for scouring out carbon formations. Figure 9 shows the rod positioned centrally within one of the tubes and spaced from the walls of the tubes by spacing lugs 63 which may be secured to the rod before insertion in the pipe. This arrangement may be desirable where the invention is conducted particularly for the high speed feature of the invention, and in cases where there seems no need for the abrading action of the rod within the pipe or tube, such as would be the case if the rod was freely movable. Figure 9 and Figure 10, which latter is a cross sectional view of the structure shown in Figure 9, illustrate the same type of hollow spacing rod as is shown in Figure 4. Figures 11-14, inclusive, illustrate a modified arrangement for the intake and outlet connection by which the oil is led first through the inner series of pipes and progressively through the next outer ones. Claims to this particular sequence of Figures 11-14 are presented in my copending application, Serial No. 583,169, filed August 21, 1922.

40 The operation of the process and the apparatus will now be described. Oil is introduced through the pipe 45, through the stuffing box, and through the length of the central pipe 4 which is thus kept full of cold oil. 45 The oil is then led through the pipe 4^b from which it passes into the pipe 12, from which latter it is conducted into the next adjacent pipe 13, and so on through each of the pipes of the series 12-40, inclusive, being introduced into one end of the pipe and discharged from the opposite end, and being reintroduced in a similar manner into an adjacent pipe. In this manner the oil is moved progressively through each of the pipes in series, first in one direction through the length of the still and then in the opposite direction in the next adjacent pipe. In the arrangement shown in Figures 2 and 3 the oil is first passed through the group of pipes 50 most distant from the center pipe 4 and then through the pipes more closely grouped about the center pipe. The particular sequence of connecting the pipes forms a part of this present invention, and the invention 55 includes the idea of heating the outer group

of pipes more intensely by having the outer group closest to the source of heat in the lower part of the furnace. After the oil has been subjected in the assembly of pipes to temperature conditions which are at least sufficient to effect cracking conditions within the pipes, the oil is led back from the pipe 40 into the discharge pipe 55 located within pipe 4 and discharged through the pipe 46. In the passage through the pipe 55, within the pipe 4, the oil serves to slightly preheat the incoming oil in the annular space immediately surrounding the pipe 55. The apparatus which thus provides for a flow of cold oil through the length of the center pipe 4 is particularly efficient because the oil serves to keep the material of the pipe fairly cool and to prevent it from overheating and weakening. There is considerable weight on the pipe 4 due to the structure of the pipe assembly carried by it, and the long extent of the pipe 4 within the furnace structure makes it particularly desirable to have the pipe filled with cold oil rather than the previously heated oil. The reason for this is apparent because it is well known that metal, such as a shaft, at a high temperature, is much more apt to become deformed under strain than the same shaft at normal temperatures. Accordingly, because the hollow shaft supports all of the weight of the retort, it is very essential to keep the shaft as cold as possible. There is another reason why the oil is initially introduced into the central shaft and first passed through the length of this shaft. This involves one of the important features of the invention which is based on the fact that the velocity of the oil within the pipe system is increased progressively as it passes through the system. The reasons for this treatment and the arrangement of apparatus which makes the process possible are described. The cross sectional area of the central hollow shaft 4 is greater than the cross sectional area of any of the surrounding pipes of the system, and thus the velocity of the oil passing through the shaft is less than the velocity of the oil passing through the individual pipes. Thus if the oil after cracking treatment and carrying carbon produced by this treatment should be introduced into the central shaft and the velocity thus lowered, carbon would tend to deposit within the shaft due to the decreased velocity. It has been found in the present invention that when an oil is cracked with the production of a fluid which may be a liquid, or a vapor, or a combination of the two, but which in any case carries carbon with it mechanically, the velocity of this liquid determines the amount of carbon which may be mechanically carried. Thus a fluid with a high velocity will transport more mechanically carried carbon than a fluid with a low velocity. It follows that when a fluid travelling at a high

70

100
105
110
115
120
125
130

velocity, and carrying the maximum amount of carbon possible at that velocity, is slowed down and its velocity decreased, some of this carbon will drop out and deposit on the walls of the pipe through which the fluid is passing. Consequently, to prevent the deposition of mechanically carried carbon, the velocity of the carbon carrying fluid should be maintained constant or increased. Furthermore, 10 it is readily seen that an ideal condition would be one in which the velocity of the fluid increased as the amount of cracking increased, or in other words, as the amount of carbon to be carried increased. To increase the velocity of a fluid it is necessary to either increase the volume of fluid flowing through a pipe or series of pipes of constant cross section, or to progressively decrease the cross section of the pipes for a constant 20 volume of fluid. It is evident that in the heat treatment of an oil in a pipe still of uniform pipe size, the first method of increasing the velocity is conducted automatically, the volume of the oil constantly increasing 25 on account of expansion due to heating and partial vaporization. To increase this effect would involve progressively decreasing the net cross sectional area of the pipes, the oil passing from large to smaller passages 30 progressively. Net cross sectional area may be defined as the total cross sectional area of a tube minus the total cross sectional area of any restriction or the sum of the cross sectional areas of any restrictions. A restriction 35 may be due to a decrease in the bore of the tube or to the presence of a rod or rods or other obstruction within the bore of the tube. This effect may be produced by a variety of constructions, such as by progressively 40 decreasing the size of the pipes in a rotatable still containing no rods, or by using rods in the group of pipes next adjacent the outlet, or by using rods of progressively increased size in the tubes from the inlet to the 45 outlet, or by increasing the number of rods progressively from the inlet to the outlet. In the present apparatus, as illustrated in Figs. 1-3 inclusive, the center shaft 4 has a larger cross sectional area than the cross 50 sectional area of the pipes of the still which are grouped about the center shaft. The difference in cross sectional area is accentuated by the presence in the smaller pipes 12-40, inclusive, of rods. In the passage of oil 55 through the system, it moves relatively slowly through the large bore of the center shaft 4 and increases speed as it passes through the smaller bore of the pipes 12-40. It will be observed that only the straight portions 60 of the center shaft 4 and the pipes 12-40 inclusive, lies within the heating space and between the plates 42 of the furnace. Accordingly, the chief portion of any carbon which would tend to deposit would be along that 65 heated portion in the straight portions of the

pipes, and substantially no carbon would tend to collect within the bends joining the pipes because the bends are located outside of the furnace structure. Referring to Figs 11-14 inclusive, arrangements of pipes and tubes are shown by which the net cross sectional area of the tubes may be decreased progressively from the inlet to the outlet end. In the structure shown in these figures the oil is led first to the inner series and thence through the outer pipe. Fig. 11 shows diagrammatically the arrangement of the tubes of the still in which the diameter of the pipes used is progressively reduced from the inlet to the outlet. The central axial pipe 4 has around it three successive rows of pipes and the pipes next adjacent the center pipe are slightly larger than those of the intermediate group, and the pipes of the intermediate group are slightly smaller than the first mentioned group and slightly larger than those of the outer series. Thus, the center shaft may have a diameter of 12 inches, the next adjacent group may be 8 inches in diameter, the next group or intermediate group may be 6 inches in diameter, and the outer row may be 4 inches in diameter. In this diagrammatic representation, the last member of the outer group indicated at 40 is intended to be directly connected to the outlet pipe, 90 as indicated at 55^a in dotted lines. The first or receiving pipe of the series is indicated at 12. Oil flows from the center pipe 4 to the pipe 12, and progressively through the pipes of the inner group of pipes, to and through the intermediate group of pipes and finally to and through the outer series. In this arrangement, the ends of the pipes may be connected by return bend portions in the manner illustrated in Figs. 1, 2 and 3, although the particular direction of the return bends might be slightly different. Referring to Fig. 12, the reduction in the net cross sectional area is effected by using pipes of a uniform size and by using rods within the pipes of the outer series, that is, in the pipes next adjacent the outlet. In this case, if the central shaft has a diameter of 12 inches, the pipes of the still may have a diameter of 4 inches, and the rods in the outer group of pipes may have a diameter of 1 $\frac{1}{4}$ inches. In Fig. 13, a reduction is effected by using pipes of a uniform size and increasing the size of the rods progressively from the inner series to the outer series. Thus, if the central shaft has a diameter of 12 inches, each of the pipes may be 4 inches in diameter. Rods 1 inch in diameter may be used in the inner group, of pipes, rods 1 $\frac{1}{2}$ inches in diameter in the intermediate group, and rods 2 inches in diameter in the outer group. In Fig. 14, the reduction in the net cross sectional area is obtained by using a progressively increasing number of rods in pipes of uniform size. Thus, if the central shaft is 12 130

inches, the pipes may have a diameter of 4 inches. In the inner group, a single rod having a diameter of 1 inch each is used. In the outer group, three rods of 1 inch each are used.

5 In this invention, where reference is made to the use of speed, the principle holds true whether carried out in stationary or moving apparatus. The same high speed effect 10 might be produced if the apparatus was stationary. Thus in the present apparatus the high speed principle would be used whether the apparatus illustrated in the present invention was being rotated or whether it was 15 stationary.

No claim is made by me to the invention broadly relating to a rotatable nest of pipes and to the use of a freely movable rod within such pipes.

20 Claims directed to the passage of the cold oil from the center shaft first through the inner pipes and thence to the outer pipes and the final return from the outer pipes are presented in my copending application, 25 Serial 452,797, filed May 15, 1930.

I claim:

1. The process of producing low boiling hydrocarbon oils from high boiling hydrocarbon oils which comprises forcing liquid oil 30 to be treated at high speed into and in one direction through a tube mounted to revolve about a given center and moving the oil at relatively increased speed as compared to the prior rate of speed as it passes lengthwise of 35 a rod freely movably located in said tube and extending lengthwise thereof, subjecting the oil to a heat treatment applied directly to the exterior of the tube sufficient to effect cracking conditions therein, the increased speed of 40 movement of the oil in the region of the rod aiding to prevent deposit of carbon.

2. The process of producing low boiling hydrocarbon oils from high boiling hydrocarbon oils which comprises introducing the 45 oil to be treated under pressure and at high speed into and in one direction through a tube mounted for rotation about a given center and having in a portion thereof a freely movable rod extending lengthwise of 50 the tube, passing the oil between the rod and the interior of the tube at a speed greater than the speed of the oil in that portion of the tube not containing the rod, the increased speed of movement of the oil in the region 55 of the rod aiding to prevent deposit of carbon.

3. The process of heat treating hydrocarbon oils which comprises forcing liquid oil to be treated at high speed into a tube mounted 60 to revolve about a given center in one direction through it, moving the oil at relatively increased speed as compared to the prior rate of speed as it passes lengthwise of a rod freely movable in the tube and extending 65 lengthwise thereof and subjecting the oil to

a heat treatment applied directly to the exterior of the tube sufficient to effect volatilization conditions therein, the increased speed of movement of the oil in the region of the rod aiding to prevent deposit of carbon.

4. The process of heat treating hydrocarbon oils which comprises introducing the oil to be treated under pressure and at high speed into and in one direction through a tube mounted for rotation about a given center and having in a portion thereof a freely movable rod extending lengthwise of the tube, passing the oil between the rod and the interior of the tube at a speed greater than the speed of the oil in that portion of the tube not containing the rod, the increased speed of movement of the oil in the region of the rod aiding to prevent deposit of carbon.

5. The process of producing low boiling hydrocarbon oils from high boiling hydrocarbon oils which comprises introducing oil to be treated first into the outer members of a plurality of pipes connected in series and mounted to rotate about a center, passing the oil progressively from the outer members farthest removed from the center to the centrally located pipes, and subjecting the oil to a heat treatment applied directly to the exterior of the pipes sufficient to effect cracking conditions within at least some of the pipes.

6. The process of producing low boiling hydrocarbon oils from high boiling hydrocarbon oils which comprises introducing oil to be treated first into the outer members of a plurality of pipes connected in series and mounted to rotate about a center, passing the oil progressively from the outer members farthest removed from the center to the centrally located pipes, and subjecting the oil to a heat treatment applied directly to the exterior of the pipes sufficient to effect cracking conditions within at least some of the pipes, the heat being applied more intensely 100 to the outer pipes than to the pipes positioned centrally.

7. The process of producing low boiling hydrocarbon oils from high boiling hydrocarbon oils which comprises introducing oil to be treated first into the outer members of a plurality of pipes connected in series and mounted to rotate about a center and having a freely movable rod positioned in each pipe, passing the oil progressively from the outer members farthest removed from the center to the centrally located pipes, and subjecting the oil to a heat treatment applied directly to the exterior of the pipes sufficient to effect cracking conditions within at least some of the pipes.

8. The process of producing low boiling hydrocarbon oils from high boiling hydrocarbon oils which comprises introducing oil to be treated into a plurality of pipes con- 130

- 8 nected in series and mounted to rotate about a center and having a freely movable rod positioned in each pipe, passing the oil progressively from the outer members farthest removed from the center to the centrally located pipes, and subjecting the oil to a heat treatment applied directly to the exterior of the pipes sufficient to effect cracking conditions within at least some of the pipes.
- 10 9. The process of heat treating hydrocarbon oils which comprises introducing the oil to be treated first into the outer members of a plurality of pipes connected in series and mounted to rotate about a center, passing the oil progressively from the outer members farthest removed from the center to the centrally located pipes, and subjecting the oil to a heat treatment applied directly to the exterior of the pipes sufficient to the effect volatilization within at least some of the pipes.
- 15 10. The process of heat treating hydrocarbon oils which comprises introducing the oil to be treated first into the outer members of a plurality of pipes connected in series and mounted to rotate about a center, passing the oil progressively from the outer members farthest removed from the center to the centrally located pipes, and subjecting the oil to a heat treatment applied directly to the exterior of the pipes sufficient to effect volatilization within at least some of the pipes, the heat being applied more intensely to the outer pipes than to the pipes positioned centrally.
- 20 11. The process of heat treating hydrocarbon oils which comprises introducing the oil to be treated first into the outer members of a plurality of pipes connected in series and mounted to rotate about a center and having a freely movable rod positioned in each pipe, passing the oil progressively from the outer members farthest removed from the center to the centrally located pipes, and subjecting the oil to a heat treatment applied directly to the exterior of the pipes sufficient to effect volatilization within at least some of the pipes.
- 25 12. The process of heat treating hydrocarbon oils which comprises introducing the oil to be treated into a plurality of pipes connected in series and mounted to rotate about a center and having a freely movable rod positioned in each pipe, passing the oil progressively from the outer members farthest removed from the center to the centrally located pipes, and subjecting the oil to a heat treatment applied directly to the exterior of the pipes sufficient to effect volatilization within at least some of the pipes.
- 30 13. Apparatus for heat treating hydrocarbon oil material comprising a rotatable axle tubular throughout its length, a pipe extending parallel to said axle and in communication with the interior of said axle and revolvable about it, a rod within said pipe and
- 35 extending lengthwise thereof, and means for introducing material to said pipe through said axle, said rod having a cross sectional area at least as great as one half the bore of the pipe.
- 40 14. Apparatus for heat treating hydrocarbon oil material comprising a plurality of pipes connected in series and mounted to rotate about a fixed axis, and a freely movable rod in each of said pipes extending lengthwise thereof, each rod having a cross sectional area at least as great as one half the bore of the pipe.
- 45 15. Apparatus for heat treating hydrocarbon oil material comprising a rotatable axle tubular throughout its length, a pipe extending parallel to said axle and in communication with the interior of said axle and revolvable about it, a freely movable rod within said pipe and extending lengthwise thereof, and means for introducing material to said pipe through said axle, said rod having a cross sectional area at least as great as one half the bore of the pipe.
- 50 16. The process of producing low boiling hydrocarbon oils from high boiling hydrocarbon oils which comprises forcing liquid oil to be treated at high speed into and in one direction through a tube mounted to revolve about a given center and having therein a rod extending lengthwise of the tube and spaced from the wall thereof, moving the oil at relatively increased speed as it passes the rod, and as compared to the speed before reaching the rod, and subjecting the oil to a heat treatment applied directly to the exterior of the tube sufficient to effect cracking conditions therein.
- 55 17. Apparatus for heat treating hydrocarbon oil material comprising a plurality of substantially parallel pipes mounted to rotate about a fixed axis, a plurality of pipe bends each connecting with the adjacent ends of pairs of pipes to be connected, and a rod removably mounted in each of said pipes and extending lengthwise thereof and spaced from the inner wall thereof and supported independently of said pipe bends.
- 60 18. Apparatus for heat treating hydrocarbon oils comprising a plurality of substantially parallel pipes connected in series and mounted to rotate about a fixed axis, a plurality of pipe bends each connecting with the adjacent ends of pairs of pipes to be connected, and a straight rod removably mounted in each of said pipes and extending lengthwise thereof and spaced from the inner wall thereof and supported independently of said bends, each of said rods having a cross sectional area at least as great as one-half the cross sectional area of the pipe in which it is positioned.
- 65 19. Apparatus for heat treating hydrocarbon oil material comprising a rotatable hollow axle, a first pipe extending parallel to

said hollow axle and revoluble about it, a second pipe connected to said hollow axle for the introduction of oil to be treated, a third pipe extending from said hollow axle to said 5 first pipe and providing communication for oil between said hollow axle and said first pipe, and a furnace embracing a portion of said hollow axle and said first pipe and having both of its opposite end walls located between said third pipe and said second pipe.

20. Apparatus for heat treating hydrocarbon oil material comprising a rotatable hollow axle, a first pipe extending parallel to said hollow axle and revoluble about it, a 15 second pipe connected to said hollow axle for the introduction of oil to be treated, a third pipe extending from said hollow axle to said first pipe and providing communication for oil between said hollow axle and 20 said first pipe, a bearing supporting said hollow axle at a point between said second pipe and said third pipe, and a furnace embracing a portion of said hollow axle and said first pipe and having both of its opposite end 25 walls located between said bearing and said third pipe.

21. Apparatus for heat treating hydrocarbon oil material comprising a rotatable hollow axle, a first pipe extending parallel to 30 said hollow axle and revoluble about it, a second pipe connected to said hollow axle for the introduction of oil to be treated, a third pipe extending from said hollow axle to said first pipe and providing communication for 35 oil between said hollow axle and said first pipe, a bearing supporting said hollow axle at a point between said second pipe and the plane of revolution of said first pipe, and a furnace embracing a portion of said 40 hollow axle and said first pipe and having both of its opposite end walls located between said bearing and said third pipe.

22. Apparatus for heat treating hydrocarbon oil material comprising a rotatable hollow axle, a first pipe extending parallel to 45 said hollow axle and revoluble about it, a second pipe connected to said hollow axle for the introduction of oil to be treated, a third pipe extending from said hollow axle 50 to said first pipe and providing communication for oil between said hollow axle and said first pipe, a bearing supporting said hollow axle at a point between said second pipe and said third pipe, a furnace embracing a portion 55 of said hollow axle and said first pipe and located between said bearing and said third pipe, and a discharge pipe for hot oil in ported communication with said first pipe and revoluble therewith and extending centrally 60 toward said hollow axle, into it, and thence centrally therethrough and in spaced relation from the walls thereof and past said bearing.

23. Apparatus for heat treating hydrocarbon oil material comprising a rotatable hol-

low axle, a first pipe extending parallel to said hollow axle and revoluble about it, a second pipe connected to said hollow axle for the introduction of oil to be treated, a third pipe extending from said hollow axle to said 70 first pipe and providing communication for oil between said hollow axle and said first pipe, a bearing supporting said hollow axle at a point between said second pipe and the plane of revolution of said first pipe, a furnace embracing a portion of said hollow axle and said first pipe and located between said bearing and said third pipe, and a discharge pipe for hot oil in ported communication with said first pipe and revoluble therewith and extending centrally toward said hollow axle, into it, and thence centrally therethrough and in spaced relation from the walls thereof and past said bearing.

24. Apparatus for heat treating hydrocarbon oil material comprising a rotatable hollow axle, a plurality of pipes connected in series and extending parallel to said hollow axle and revoluble about it, an inlet pipe connected to said hollow axle for the introduction of oil to be treated, an intermediate pipe extending from said hollow axle to said plurality of pipes and providing communication for oil between said hollow axle and said plurality of pipes, and a furnace embracing a portion of said hollow axle and said plurality of pipes and having both of its opposite end walls located between said 90 inlet pipe and said intermediate pipe.

25. Apparatus for heat treating hydrocarbon oil material comprising a rotatable hollow axle, a plurality of pipes connected in series and extending parallel to said hollow axle and revoluble about it, an inlet pipe connected to said hollow axle for the introduction of oil to be treated, an intermediate pipe extending from said hollow axle to said plurality of pipes and providing communication for oil between said hollow axle and said plurality of pipes, a bearing supporting said hollow axle at a point between said inlet pipe and said intermediate pipe, and a furnace embracing a portion of said hollow axle and said plurality of pipes and having both of its opposite end walls located between said bearing and said intermediate pipe.

26. Apparatus for heat treating hydrocarbon oil material comprising a rotatable hollow axle, a plurality of pipes connected in series and extending parallel to said hollow axle and revoluble about it, an inlet pipe connected to said hollow axle for the introduction of oil to be treated, an intermediate pipe extending from said hollow axle to said plurality of pipes and providing communication for oil between said hollow axle and said plurality of pipes, a bearing supporting said hollow axle at a point between said inlet pipe and the plane of revolution of said plurality of pipes, and a furnace embracing a

portion of said hollow axle and said plurality of pipes and having both of its opposite end walls located between said bearing and said intermediate pipe.

27. Apparatus for heat treating hydrocarbon oil material comprising a rotatable hollow axle, a plurality of pipes connected in series and extending parallel to said hollow axle and revoluble about it, an inlet pipe connected to said hollow axle for the introduction of oil to be treated, an intermediate pipe extending from said hollow axle to said plurality of pipes and providing communication for oil between said hollow axle and said plurality of pipes, a bearing supporting said hollow axle at a point between said inlet pipe and said intermediate pipe, a furnace embracing a portion of said hollow axle and said plurality of pipes and located between said bearing and said intermediate pipe, and a discharge pipe for hot oil connected to and in ported communication with said plurality of pipes and revoluble therewith and extending centrally towards said hollow axle, into it, and thence centrally therethrough and in spaced relation from the walls thereof and past said bearing.

28. Apparatus for heat treating hydrocarbon oil material comprising a rotatable hollow axle, a plurality of pipes connected in series and extending parallel to said hollow axle and revoluble about it, an inlet pipe connected to said hollow axle for the introduction of oil to be treated, an intermediate pipe extending from said hollow axle to said plurality of pipes and providing communication for oil between said hollow axle and said plurality of pipes, a bearing supporting said hollow axle at a point between said inlet pipe and the plane of revolution of said plurality of pipes, a furnace embracing a portion of said hollow axle and said plurality of pipes and located between said bearing and said intermediate pipe, and a discharge pipe for hot oil connected to and in ported communication with said plurality of pipes and revoluble therewith and extending centrally towards said hollow axle, into it, and thence centrally therethrough and in spaced relation from the walls thereof and past said bearing.

29. Apparatus for heating hydrocarbon oils comprising a furnace, a rotatable pipe assembly comprising a plurality of pipes connected in series and within said furnace, said assembly having an initial heating chamber and a final outlet pipe, the net cross sectional capacity of said initial heating chamber being greater than the cross sectional capacity of the general average of all of the pipes of said system between said initial treatment chamber and said outlet pipe.

In testimony whereof I affix my signature.

DAVID E. DAY,
